RAZOR DRIVE MECHANISM

Ingvar Lonne, Burbank, Calif.

Application January 24, 1945, Serial No. 574,290

6 Claims. (Cl. 30—43)

1

My invention relates to razors, particularly to the type known as mechanically operated or electric razors.

This application is a continuation in part of my co-pending application for Blade, Serial No. 560,625, filed October 27, 1944 which matured as Patent No. 2,445,625 issued on July 27, 1948.

One of the principal objects of this invention is to provide a novel means for operating an inner shear member of a razor with respect to an outer shear member.

Another object of this invention is to provide a novel resilient connection between the movable shear member and the means for operating the same, whereby substantially all wear between the shear members and between the movable shear member and the operating means is automatically taken up, thereby increasing the efficiency of the shearing means and the smooth and silent operation thereof.

An important object also of this invention is to provide, as a whole, a novel connection between a reciprocating and an oscillating drive member for automatically taking up any loose connection or lost motion between such members.

A further object of this invention is to provide a novel connection between a drive shaft or an eccentric on the drive shaft with an oscillating member for further reducing wear to a minimum, and thereby increasing the smooth and silent operation of such portion of the mechanism.

With these and other objects in view, as will appear hereinafter, I have devised a mechanical razor having certain novel features of construction, combination, and arrangement of parts and portions, as will be hereinafter described in detail and particularly set forth in the appended claims, reference being had to the accompanying drawings, and to the characters of reference thereon, which form a part of this application, in which:

Fig. 1 is a view taken on the median line of a preferred form of my razor, the section being taken through 1—1 of Fig. 2;

Fig. 2 is a partial sectional view thereof taken through 2—2 of Fig. 1;

Fig. 3 is a fragmentary sectional view thereof, taken through 3—3 of Fig. 2, showing primarily the mechanical drive connection between the drive shaft and the movable shear member;

Fig. 4 is a wiring diagram of the electric motor of my razor; and,

Fig. 5 is a fragmentary view of the circuit breaker of my electric motor in a slightly modified form.

2

The razor shown in the drawings is shaped exteriorly similar to the conventional electric razor or shaver. It is enclosed in a split housing 1 and is provided at one end with a stationary blade or shear member 2 in which is reciprocally mounted a removable or reciprocating blade or shear member 3.

Within the middle portion of the housing is positioned an electric motor M having a motor shaft 10, the axis of which extends perpendicularly to the plane of reciprocation of the shear member 3. The shaft is revolvably mounted on bearing plates 11, one secured to a shoulder in each half of the split housing 1. Near one end 10 of the shaft is provided an eccentric 12 on which is mounted one end of a link 13, which is preferably made of insulating material, such as Bakelite. The free end of the link is connected to the inner end of an oscillating member 14. This oscillating member is pivotally mounted intermediate its ends, but near the other or outer end, on a pivot screw 15 which is secured in one member of the housing 1. The latter end of the oscillating member 14 is reduced, as indicated by 14^a, and this reduced end extends toward the inner or movable shear member 3. Over the reduced end 14^a of the oscillating member is positioned the leaf spring 16. This spring consists of an inner leg 16^a which fits over the reduced portion 14^a, and is seated against a shoulder 14^b at the inner end of the reduced portion. The outer end of the spring has a U-shaped portion 16^b with an enlarged or looped end, providing substantially a roller or cylinder which fits into a recess 3^a 35 provided at the inner side of the movable shear member 3, said recess being positioned transversely with respect to the direction of reciprocation of the shear member. The reduced end 14^a of the oscillating member extends into the 40 U-shaped portion of the spring, short of the end of the loop, for locating the outer or U-shaped portion of the spring. The U-shaped portion 16^b is connected with the leg 16^a by means of a loop 16^c.

45 By reason of such construction, the enlarged roller part at the end of the U-shaped portion resiliently seats the end of the oscillating member in the recess 3^a, and this enlarged or roller part of the bifurcated portion 16^b is resiliently forced into the recess 3^a by the loop 16^c.

The shaft 10 is the rotor shaft of the motor, and on it is mounted the rotor consisting of an armature 17. The motor is shown as being provided with two field coils 18 in line with each other and with the longitudinal axis of the hous-

ing. The source of energy for the razor is supplied from electric terminals 19 at the end of the housing opposite the blades or shear members 2 and 3. One of the terminals is connected with one of the field coils while the other terminal is connected with the other field coil. In series with the connection between two field coils is a circuit breaker 20 consisting of a stationary contact 20^a and a movable contact 20^b, the latter being provided at the end of a lever 20^c pivotally mounted at its opposite end on a pin 21 within the housing. The contacts 20^a and 20^b are normally held in engagement by means of a torsion spring 22 extending around the pivot pin 21.

In the modified form of construction, shown in Fig. 5, the contact 20^b of the lever 20^c is forced towards or in engagement with the contact 20^a by means of a coil spring 23.

The motor shaft 10 is provided with cams 10^a at its opposite sides, these cams being shown as merely flattened portions at the opposite sides of the shaft 10. The inner or under side of the lever 20^c has an insulating bearing plate 24 which is engaged by the cams or cam portions 10^a for rocking the lever 20^c about its pivotal axis against the tension of the spring 22 or 23, thereby breaking the engagement of the contact 20^a and 20^b, and the motor circuit.

The oscillating member 14 is connected to one end portion of the shaft 10 while the circuit breaker is provided at the opposite end of the shaft. It will be here noted that the connection of the oscillating member with the link 13 is between the link and the adjacent bearing plate 11. The oscillating member is bent outwardly around the field coil and then inwardly to form the pivoted portion for the oscillating member. The reduced portion 14^a of the oscillating member is located at approximately the central portion of the housing, and the aforementioned pivoted portion of the oscillating member is offset outwardly therefrom, substantially as shown in Fig. 2.

To the shaft 10, and coaxially therewith, is secured a starting wheel 26 which extends through one side of the housing 1. This wheel is adapted for starting the motor M in the event it rests at a dead center.

Though I have shown and described a particular construction, combination, and arrangement of parts and portions, I do not wish to be limited to the same, but desire to include in the scope of my invention the construction, combination, and arrangement substantially as set forth in the appended claims.

I claim:

1. In a razor of the class described, a support, a movable member reciprocally mounted thereon, an elongated oscillating member pivotally mounted intermediate its ends on the support and having one end connected to the movable member, a drive shaft on the support, and a link eccentrically connected at one end to the shaft and at its other end to the opposite end of the oscillating member, the axis of the eccentric connection of the link with the shaft being parallel to the pivotal axis of the oscillating member.

2. In a razor of the class described, a support, a movable member reciprocally mounted thereon, an elongated oscillating member pivotally

mounted intermediate its ends on the support and having one end connected to the movable member, a drive shaft on the support, an eccentric, and a link connected at one end to the eccentric and at its other end to the opposite end of the oscillating member, the axis of the eccentric being parallel to the pivotal axis of the oscillating member.

3. In a razor of the class described, a support, a movable member reciprocally mounted thereon, an oscillating member pivotally mounted intermediate its ends on the support and having one end yieldably connected to the movable member, a drive shaft mounted on the support on an axis parallel to the pivotal axis of the oscillating member, and a link eccentrically connected at one end to the shaft and at its other end to the opposite end of the oscillating member.

4. In a razor of the class described, a housing, a stationary shear member, a movable shear member reciprocally mounted adjacent the former, an elongated oscillating member pivotally mounted intermediate its ends in the housing with one end connected with the movable shear member, a drive shaft in the housing, and a link eccentrically connected at one end to the shaft and at its other end to the opposite end of the oscillating member, the axis of the eccentric connection of the link with the shaft being parallel to the pivotal axis of the oscillating member.

5. In a razor of the class described, a housing, a stationary shear member, a movable shear member reciprocally mounted adjacent the former, an elongated oscillating member pivotally mounted intermediate its ends in the housing with one end connected with the movable shear member, a drive shaft in the housing, an eccentric, and a link connected at one end to the eccentric and at its other end to the opposite end of the oscillating member, the axis of the eccentric being parallel to the pivotal axis of the oscillating member.

6. In a razor of the class described, a support, a shear member movably mounted on the support, an oscillating member on the support for moving the shear member, and means operatively connecting the free end of the oscillating member to the shear member, said shear member having a cylindrical recess of more than semi-circular extent and the connecting means having a cylindrical portion of more than semi-circular extent rockingly positioned in the recess, the free end of the oscillating member being slidable with respect to the connecting means in a direction at right angles to the axis of said cylindrical portion.
